CONVERTER COUPLING FOR VACUUM
CLEANERSLloyd W. Pardee, Lakewood, Ohio, assignor to
The Scott & Fetzer Company, Cleveland,
Ohio, a corporation of Ohio

Application June 3, 1937, Serial No. 146,192

3 Claims. (Cl. 15--9)

This invention relates to electric suction cleaners of the portable type and it has for its objects the provision of a new, simplified and improved extension connection for vacuum cleaners, which 5 may be quickly and readily attached to the cleaner and which does not require the need of close fitting or accurately machined surfaces to provide a leak-proof connection.

These and other objects of the invention will 10 become more apparent and better understood after consideration has been given to the following detailed description of the invention taken in connection with the drawing which shows, merely by way of illustration, structure adapted 15 for carrying out the objects of the invention.

In the drawing accompanying and forming a part of this application, Figures 1 and 2 are side elevational views, partly in section, of a suction cleaner equipped with a motor driven brush; 20 Figure 1 showing the cleaner without the extension hose connection or coupling member and Figure 2 showing the cleaner with hose connection in place; and Figure 3 is an enlarged detail side elevational view of the coupling member.

25 A suction cleaner of the so-called horizontal type has been selected for the purpose of illustrating an embodiment of the invention. Such a cleaner comprises a rigid casing defining a motor housing 1, a fan casing 2 and a collecting 30 nozzle 3 arranged in the order named from rear to front and mounted on suitable wheels 4, 4 so that the inlet mouth 5 with which the nozzle is provided is located substantially parallel with and in close proximity to the supporting surface.

35 A propelling handle (not shown) is attached to the device in some suitable way as by means of trunnions 6, 6 carried one at each side of the motor housing. A fan 7 inside the fan casing 2 is carried on the shaft 8 of the motor (not shown) 40 and a peripheral part of the fan casing is provided with an outlet neck 9 adapted for reception of a dust bag (not shown) whereby dust and dirt are separated from the air before it is allowed to escape from the bag.

45 In the lower portion of the nozzle 3, a brush 10 is rotatably mounted. The brush is driven by means of a belt 11 which is adapted for engagement with a pulley 12 located at the outermost end of the motor shaft 8. The nozzle 3 communicates with the fan casing by way of a fan case inlet 13. The front wall of the nozzle is provided with an opening 14 in alignment with the fan case opening. A removable cover 15 is provided for the opening 14. The opening 14 is 50 somewhat smaller than the fan case inlet so that

the cover 15 may be kept as small as possible for the sake of the appearance of the cleaner.

When it is desired to use the extension or dusting tools of the cleaner, the cover 15 may be removed and a dusting tool converter or coupling member 16 may be inserted and adjusted in the opening 14 after the manner indicated in Figure 2 of the drawing. This coupling comprises a body portion in the form of a section of tubing 17 with side guide wings 18, 18 and one or more lower guide wings 20. A spring fastener or latch 21 is riveted at 22 to the top portion of the tube. The forward end of the spring is guided between a pair of arms or lugs 23 which may be formed integral with the tube 17. The spring 21 is also provided with a notched portion 24 which engages with the inner surface of the nozzle when the coupling device is in place.

The opening 14 of the nozzle is slightly larger than the diameter of the tube 17. One end of the tube 17 is provided with a flexible rubber flange or annulus 25 which is of such diameter and thickness as to be easily inserted through the opening 14 while at the same time sealing the tube 17 with respect to the fan case inlet 13 when the coupling is in position for use. The annulus 25 is preferably vulcanized to the end portion of a liner or sleeve 26 which is held in place in the tube 17 by means of the rivets 22. The forward end of the tube 17 is adapted to receive one end of a flexible hose 27 by means of which the fan case inlet is connected to one or the other of a number of attachment or utility tools which may be connected to the other end of the hose 27.

The present arrangement has the advantage 35 of not requiring extremely accurate alignment of the fan case and nozzle openings 13 and 14 respectively. The use of a rubber sealing ring such as the one indicated at 25 eliminates the need of providing accurately machined surfaces to contact with the tube 17, for when the device is in use, the suction in the fan case will ordinarily be sufficient to cause the ring 25 to seal about the inlet mouth of the fan case in air-tight relation if it has not already done so.

When one is finished using the attachments, the coupling may be readily removed by simply depressing the end of the spring 21 whereupon the coupling is freed for removal from the nozzle and after the belt 11 has been replaced on the pulley 12 and the cover 15 has been applied, the machine is in condition to be used as an ordinary vacuum cleaner.

The foregoing description and the accompanying drawing to which it relates, describes what

might be termed the preferred mode of practicing the invention. It is to be clearly understood, however, that the invention includes each and every novel feature or combination of novel features herein disclosed, subject only to the restrictions of the prior art, and that the invention may assume other forms and it is not to be limited to the particular and specific structure shown and described herein.

10 Having thus described my invention what I claim is:

1. A suction cleaner comprising a fan chamber having a centrally arranged inlet, a floor cleaning nozzle depending from said chamber, 15 the upper end of said nozzle surrounding said inlet, an opening in said nozzle in alignment with said inlet adapted to receive and position a dusting tool coupling in operative position in said inlet, a dusting tool coupling having one end thereof secured to a dusting tool conduit and the other end thereof provided with a flexible rubber annulus proportioned to overlap the edges of said inlet and be drawn into engagement throughout the overlapped edge area by suction in the fan chamber.
2. A suction cleaner comprising a fan chamber having a motor-driven fan arranged therein and a forward wall with an inlet coaxial with the fan, a floor cleaning nozzle extending from the fan chamber and shaped to surround said inlet, an opening in said nozzle adapted to receive and position a dusting tool coupling, a dusting tool coupling having one end thereof secured to a dusting tool conduit and the other end thereof provided with a flexible annulus

proportioned to overlap the edges of said inlet and be drawn into engagement throughout the overlapped edge area by the suction in the fan chamber, said coupling being provided with a spring-pressed latch arranged to bear against the opening in the nozzle to restrain bodily movement of the coupling away from the inlet opening in the fan chamber.

3. A suction cleaner comprising a fan chamber having a centrally arranged inlet, a floor 10 cleaning nozzle extending away from said inlet and proportioned at one end thereof to surround the inlet, a fan mounted in said fan chamber provided with a driving shaft adapted to extend through the inlet and into the nozzle, 15 a floor cleaning brush mounted at the end of the nozzle remote from said inlet, said nozzle also provided with an opening in alignment with said inlet, adapted to receive and position a dusting tool coupling adapted to be arranged 20 within said nozzle transversely of said brush and coaxially of said shaft, said coupling secured to a dusting tool conduit at one end and the other, end thereof being provided with a soft, flexible, non-metallic annulus proportioned to overlap the 25 peripheral edge of said inlet and be drawn into engagement throughout the overlapped edge area by the suction in the fan chamber, means carried by the outer wall of said coupling intermediate the ends thereof to restrain bodily 30 movement of the coupling away from the inlet and insure that said annulus will be properly positioned in overlapping edge engagement with the periphery of the inlet.

LLOYD W. PARDEE. 35
